HAROLD B. ZIEGLER, OF SHAWNEE, OKLAHOMA, ASSIGNOR OF ONE-HALF TO DELL BAKER, OF SHAWNEE, OKLAHOMA

BACK PRESSURE VALVE FOR DRILL PIPE TESTING

Application filed September 19, 1932. Serial No. 683,913.

The object of the invention is to provide a back pressure valve particularly adapted for application to the lower extremity of well pipe when lowering the same into a well or fluid filled drill hole, so that there may be prevented the entrance of any fluid into the pipe prior to its reaching the bottom or rat hole shoulder; to provide a back pressure valve which may be readily released on imparting a slight angular or turning movement to the drill pipe after the latter has reached bottom; and generally to provide a valve of the kind indicated which is of simple form and susceptible of cheap manufacture.

With this object in view, the invention consists in a construction and combination of parts of which a preferred embodiment is illustrated in the accompanying drawing but to which embodiment the invention is not to be restricted. Continued use in practice may dictate certain changes or alterations and the right is claimed to make any which fall within the scope of the annexed claims.

In the drawing:

Figure 1 is a central vertical sectional view of the invention.

Figure 2 is an exterior elevational view.

Figure 3 is a sectional view on the plane indicated by the line 3-3 of Figure 1.

The valve 10 constituting the invention is formed with a conical terminal 11 arranged to engage a replaceable seat ring 12, the latter being carried in the lower end of a bushing 14 which is mounted in the upper end of the valve mandrel 15, having a threaded engagement with the latter as indicated at 16.

The valve 10 is reduced in cross section as respects the bore of the mandrel 15 but at its lower end is enlarged as indicated at 17 to provide a shouldered portion which fits snugly in the mandrel but slides freely in the same. The shouldered portion, thus keeps the valve aligned for engagement with its seat.

The valve is formed with a longitudinal bore 18 opening on the under side of the 50 shouldered portion and extending close to

the nose portion 11, where lateral ports 19 are formed effecting communication between the exterior of the valve and the bore 18. The ports are arranged at uniformly spaced angular distances around the valve.

Mounted in the mandrel and extending through suitable openings in diametrically opposite sides of the wall thereof are the valve releasing dogs 20, these dogs being of curved form with their noses 21 bearing on the top face of the shouldered portion 17 and when the valve is seated against the seat ring 12, the heel portions 22 of the dogs project beyond the periphery of the mandrel.

The valve is held yieldingly on its seat through the instrumentality of a coil spring 23, the latter being wound to fit the bore of the mandrel and having the one end abutting the under face of the shouldered portion and the other end abutting the upper end of a nipple 24, threadingly engaged with the bore of the mandrel as indicated at 25.

The mandrel at the upper end is connected with the lower end of a bushing 26 designed to be mounted at the lower end of the string of pipe being lowered in the well or fluid filled hole.

A body housing 27 to the upper end of 80 which there is threadedly connected a bushing 28, surrounds the nipple 25 and the lower end of the mandrel 15, the bushing 28 having the corner of its bore rounded as indicated at 29 and being provided on the 85 upper end with a seal ring 30, made preferably of lead and seated in a recess formed in the end of the bushing. Provision is made for positively connecting the mandrel 15 with the bushing 28 or releasing it therefrom and this provision resides in a coupling ring 31 interiorly threaded to be engaged with a reduced extremity 32 of the valve mandrel and brought into abutting engagement with the shoulder 33 on the 90 mandrel. The thread effecting connection between the coupling ring and the mandrel is relatively fine. Externally, however, the coupling ring is formed with a coarse thread 34, the ring being of frusto-conical 95 100

shape exteriorly and said coarse thread being formed on this exterior surface to engage a correspondingly formed thread arranged in a conically formed counterbore 5 in the lower end of the bushing 28.

The bushing 26 is connected to the lower end of the lowermost length of pipe being lowered into a well or drill hole and when the coupling ring 31 is engaged with the 10 threaded counterbore of the bushing 28, relative movement between the mandrel and the bushing 28 is precluded and the valve 10 is held yieldingly in engagement with its seat ring through the action of the spring 15 23. The pipe can thus be readily lowered in the well without the creation of any back pressure in the same, since the lower end is effectively closed by the action of the valve. When the pipe reaches the bottom 20 of the hole, however, the housing abuts the bottom and the valve may then be opened by imparting a slight angular or turning movement to the length of pipe from the exterior surface, this movement resulting in 25 releasing the coupling ring from the bushing 28 by unscrewing it from the latter. Since the housing 27 can descend no further, the release of the coupling ring will permit the string of pipe by its weight to 30 move the mandrel 15 axially down through the bushing 28, when the tail portions of the dogs 20 abut the rounded edge 29 thus rocking the dogs inwardly and forcing their noses 21 downwardly which, by reason 35 of engaging the shoulder of the valve, depress it from engagement with the seat ring 12. The tail portions of the dogs may pass within the bore of the bushing 28 and the mandrel be thus lowered until the lower end 40 of the bushing 26 engages the sealing member 30, which is preferably of lead, and prevents the entrance of any fluid at this point. Fluid may enter the pipe, however, when the valve is opened in the manner 45 aforesaid, flowing up through the nipple 24 and through the bore 18 of the valve, thence out through the ports 19 and around the nose of the valve through the bushing 14 and bushing 26 into the pipe.

50 The device is particularly serviceable in sand testing operations, when the empty drill pipe is lowered in the fluid filled hole and the valve opened as aforesaid.

55 Ports or openings 35 are provided in the mandrel in the region of the dogs 20 and these are especially useful in the sand testing operation, as they allow fluid to pass through the mandrel and equalize the hydrostatic pressure above and below the packer, 60 permitting the packer to be removed from its seat with much less pull than is ordinarily required.

While the opening movement of the valve is imparted by releasing the mandrel from 65 its engagement with the bushing 28, clos-

ing movement is automatically effected when the device is withdrawn, since the bushing 28 and connected housing 27 will not follow the upward movement of the mandrel until the latter has been raised to the point where the coupling ring engages the counterbore, when the dogs 20 are free of the bushing 28 and the spring 23 may function to seat the valve.

The invention having been described, what 75 is claimed as new and useful is:

1. A back pressure valve for terminal application to a string of pipe comprising a hollow mandrel, a ported member carried at the upper end of the mandrel, a valve slidably mounted in the mandrel, a spring yieldingly impelling the valve onto a seat formed on said ported member to close communication through the port, means for securing the mandrel to the string of pipe, a member with which the mandrel is detachably connected, and means carried by the mandrel and engageable with said member to unseat said valve when the mandrel is released from said member.

2. A back pressure valve for terminal application to a string of pipe comprising a hollow mandrel, a ported member carried at the upper end of the mandrel, a valve slidably mounted in the mandrel, a spring yieldingly impelling the valve onto a seat formed on said ported member to close communication through the port, means for securing the mandrel to the string of pipe, a housing disposed in surrounding relation to the mandrel at the lower end, a bushing coupled to said housing, a releasable coupling connecting the mandrel to the bushing, and means carried by the mandrel and engageable with said bushing to unseat the valve when the mandrel is released from said bushing.

3. A back pressure valve for terminal application to a string of pipe comprising a hollow mandrel, a ported member carried at the upper end of the mandrel, a valve slidably mounted in the mandrel, a spring yieldingly impelling the valve onto a seat formed on said ported member to close communication through the port, means for securing the mandrel to the string of pipe, a housing disposed in surrounding relation to the mandrel at the lower end, a bushing coupled to said housing, a releasable coupling connecting the mandrel to the bushing, and means carried by the mandrel and engageable with said bushing to unseat the valve when the mandrel is released from said bushing, said means comprising rockably mounted dogs extending through openings in the mandrel and having noses bearing on the valve and heel portions extending beyond the periphery of the mandrel.

4. A back pressure valve for terminal application to a string of pipe comprising a

- hollow mandrel, a ported member carried at the upper end of the mandrel, a valve slidably mounted in the mandrel, a spring yieldingly impelling the valve onto a seat released from the last said bushing and lowered therethrough.
- In testimony whereof he affixes his signature.

- 5 formed on said ported member to close communication through the port, means for securing the mandrel to the string of pipe, a housing disposed in surrounding relation to the mandrel at the lower end, a bushing 10 coupled to said housing, a releasable coupling connecting the mandrel to the bushing, and means carried by the mandrel and engageable with said bushing to unseat the valve when the mandrel is released from 15 said bushing, said means comprising rockably mounted dogs extending through openings in the mandrel and having noses bearing on the valve and heel portions extending beyond the periphery of the mandrel, and 20 said bushing being rounded on its upper inner edge for camming action against the heel portions of said dogs.
5. A back pressure valve for terminal application to a string of pipe comprising a 25 hollow mandrel, a ported member carried at the upper end of the mandrel, a valve slidably mounted in the mandrel, a spring yieldingly impelling the valve onto a seat formed on said ported member to close communication 30 through the port, means for securing the mandrel to the string of pipe, a housing disposed in surrounding relation to the mandrel at the lower end, a bushing coupled to said housing, a releasable coupling connecting 35 the mandrel to the bushing, and means carried by the mandrel and engageable with said bushing to unseat the valve when the mandrel is released from said bushing, said releasable coupling comprising a ring 40 threadingly engaged with the lower end of said mandrel and formed exteriorly with a coarse thread engageable in the lower end of said bushing to be released therefrom by an angular or turning movement imparted 45 to said mandrel.
6. A back pressure valve for terminal application to a string of pipe comprising a 50 hollow mandrel, an exterior bushing at the upper end of the same for connection to the lower end of the string of pipe, an interior bushing in the upper end of the mandrel and formed with a valve seat at its lower end, a valve slidably mounted in the mandrel, a spring yieldingly impelling the valve 55 onto said seat, a bushing in surrounding relation to the mandrel at the lower end, a coupling member coupling said bushing to the mandrel to permit its release therefrom when desired, valve releasing dogs mounted 60 in the mandrel and effective to unseat the valve by engagement with the last said bushing when the mandrel is released therefrom, and a seal ring mounted in the upper end of the last said bushing for engagement with 65 the first said bushing when the mandrel is
